UNITED STATES PATENT OFFICE.

JOSEPH KENNEDY, OF NEW YORK, N. Y.

BOLT-ANCHOR.

981,863.

Specification of Letters Patent. Patented Jan. 17, 1911.

Application filed June 24, 1910. Serial No. 568,643.

To all whom it may concern:

Be it known that I, JOSEPH KENNEDY, a citizen of the United States of America, and a resident of New York, county and State of New York, have invented certain new and useful Improvements in Bolt-Anchors, of which the following is a specification, reference being had to the accompanying drawings, forming a part thereof.

10 My invention relates to improvements in bolt anchors of the character employed for obtaining anchorage in brick or stone walls or the like wherein the material is of a character not adapted to directly receive a threaded bolt.

15 My invention consists in a longitudinally segmental anchor interiorly threaded with a double thread whereby it is adapted for use with a twin thread bolt.

20 I have found by experience in the past that when a bolt having the ordinary single thread is employed in a longitudinally segmental anchor correspondingly threaded in the interior thereof, there is a tendency of the bolt 25 to drift either to one side or the other along the line of division between the segments. This has been a source of much annoyance in that it not only distorts and injures the anchor, but it affects the alignment of the 30 bolt and reduces the efficiency of the device as a means for securing articles firmly in position. These difficulties are entirely obviated by using a double or twin thread bolt and anchor threaded correspondingly 35 thereto, by reason of the fact that the threads operate uniformly upon opposite sides of the device. I have also found that by reason of the fact that the thread projections are exactly opposite to each other in a 40 double or twin thread bolt, the wedge action is more powerful and more effective than in a single thread wherein the thread projections upon opposite sides are necessarily in staggered relation. The employment of 45 twin or double threads is further advantageous in that the bolts can be inserted and removed more rapidly.

50 My invention also consists in constructing the walls of the thread depressions and 55 projections upon substantially vertical lines upon one side thereof and oblique on the other side thereof, whereby the obliquity of the threads is upon one side thereof only.

By this means a flatter surface may be presented to the threads of the bolt without an

undue amount of the metal being cut away between the threads.

In order that my invention may be thoroughly understood, I will now proceed to describe an embodiment thereof, having 60 reference to the accompanying drawings illustrating the same, and will then point out the novel features in claims.

In the drawings: Figure 1 is a view in central transverse section through a bolt 65 anchor constructed in accordance with my invention, showing the same inserted in an opening in a wall and with a bolt partly inserted therein. Fig. 2 is a view in longitudinal section therethrough at right angles 70 to the point of view of Fig. 1, the bolt being shown as completely inserted and the anchor segments expanded. Fig. 3 is a transverse sectional view through the anchor and bolt upon the line 3-3 of Fig. 1. Fig. 75 4 is an enlarged view in longitudinal section through a portion of the bolt. Fig. 5 is a view in central longitudinal section through a slightly modified form of anchor showing a counter sunk head wood screw in 80 connection therewith. Fig. 6 is a transverse sectional view upon the line 6-6 of the screw and anchor shown in Fig. 5.

Referring first of all to the anchor shown in Figs. 1 to 3 inclusive the same comprises 85 a shell 10 longitudinally divided throughout the greater portion of its length by means of slots 11, whereby the said shell, as a whole, comprises in effect two longitudinal tubular segments. This shell has a longitudinal bore, 90 the forward end 12 of which is preferably of slightly larger diameter than the remaining portion whereby to form an open throat to receive and guide the bolt to be employed therewith, the remaining portion of the bore 95 being interiorly threaded, as at 13, with a double screw thread, the inner extremity of the shell being conveniently inwardly convergent as is shown at 14. Preferably the threads have one wall as 15 substantially at 100 right angles to the axis of the anchor, while the other wall 16 is considerably oblique thereto. A bolt 17 having a double thread to correspond with the double thread of the anchor is arranged to be employed in connection with the said anchor, the threads thereof being likewise substantially vertical upon one side thereof and considerably oblique thereto upon the opposite side.

In Fig. 1 of the drawing the portions of 110

one of the double threads upon the side of the bolt away from the spectator is indicated in dotted lines so that the relative positions of the double threads may be readily determined.

In operation the anchor is disposed in a slightly undercut opening 18 prepared to receive it, and the bolt is then inserted. As the bolt is driven home it expands the inner 10 end of the anchor, forcing the segments apart. In this form of anchor the shell is preferably made of a soft metal such as lead or lead composition, and the segments will be bent and swaged to conform to the configuration of the hole by the bolt as it is forced inward, as will be well understood by those familiar with this art. The double threads acting uniformly on both sides of the axial center of the bolt and anchor will 20 have the tendency to apply a uniform wedging action in both directions thereby obviating any tendency of the bolt to drift, and in addition thereto the form of the threads, in which the inclination is substantially all 25 upon one side of lines at right angles to the axis of the bolt and anchor will result in a powerful wedging action whereby to secure the anchor firmly in position. Reference may be had to Fig. 4 which shows upon an 30 enlarged scale, the relative positions of the opposite threads and substantially the contour thereof.

It will of course be understood that in the broad aspect of my invention I am in no way 35 limited to the class of anchor shell I employ, or the material of which it is made, or the manner in which it is formed, and in Figs. 5 and 6 I have shown in longitudinal and transverse section an anchor longitudinally 40 divided from end to end into two parts; the segments whereof are made of hard metal such as brass or iron. The two sections may be held together by any suitable means as by means of a spring clip 19. I have shown 45 this particular form of shell in combination with a counter sunk head wood screw 20 of ordinary construction except that it has twin threads 21 of the form previously described, and as the shank of this form of screw is 50 usually longitudinally tapered, I have correspondingly tapered the bore of the shell

as at 22, clear from the inner end up to the open throat.

It will be understood that while for practical purpose a double thread will be the best form, it will be noted that a similar action and disposition of the thread projections upon the opposite sides thereof, would be attained by threads formed as multiples of two, and hence while the description herein 60 is, for clearness, specific to two threads, it will equally apply to quadruple or sextuple threads.

What I claim is:

1. In a bolt anchor the combination with 65 an interiorly threaded shell, the thread depressions upon opposite sides thereof in a central longitudinal plane therethrough, being in direct lines with each other in the said plane and at right angles to the axis of the 70 shell, of a correspondingly threaded bolt for co-action therewith.

2. In a bolt anchor the combination with 75 a tubular shell composed of longitudinal segments, the said shell having an inwardly convergent bore therethrough provided with helical projections and depressions constituting a double thread, of a correspondingly double threaded bolt for co-action therewith.

3. In a bolt anchor the combination with 80 an expandible shell having a longitudinal bore therethrough and provided with helical depressions and projections constituting internal screw threads, the walls whereof upon one side are substantially vertical, and upon 85 the opposite side are oblique thereto, of a correspondingly threaded bolt for co-action therewith.

4. In a bolt anchor the combination with 90 an expandible shell having a longitudinal bore therethrough and provided with helical depressions and projections constituting double screw threads, the walls whereof upon one side are substantially vertical and upon 95 the opposite side are oblique thereto, of a correspondingly double threaded bolt for co-action therewith.

JOSEPH KENNEDY.
